Patented Apr. 11, 1961

190,090

COMBINED TONGS, NUTCRACKER, AND CONTAINER OPENER

Henry Diaz, Sr., 731 NW. 20th Ave., Miami, Fla.

Filed Sept. 30, 1960, Ser. No. 62,318

Term of patent 7 years

(Cl. D44—4)

I claim:

The ornamental design for a combined tongs, nutcracker and container opener, as shown.
